US00D984196S

(12) **United States Design Patent** (10) Patent No.: **US D984,196 S**
(45) Date of Patent: **** Apr. 25, 2023**

(54) **AIR FRYER LINER**

(71) Applicant: **Suzhou Wanjiade Technology Co., Ltd.**, Suzhou (CN)

(72) Inventor: **Minlong Wang**, Suzhou (CN)

(73) Assignee: **Suzhou Wanjiade Technology Co., Ltd.**, Suzhou (CN)

(**) Term: **15 Years**

(21) Appl. No.: **29/884,126**

(22) Filed: **Feb. 8, 2023**

(51) LOC (14) Cl. **07-02**

(52) U.S. Cl. **USPC D7/354**
